Primary Examiner — Robert M Spear

Assistant Examiner — Marissa J Cash

(74) Attorney, Agent, or Firm — Robert J. Lauson;
Lauson & Tarver LLP(57) **CLAIM**

I claim the ornamental design for a double cigar cutter, as shown and described.

DESCRIPTION

FIG. 1 is a top perspective view of a double cigar cutter. FIG. 2 is an bottom perspective view of a double cigar cutter.

FIG. 3 is a top view of a double cigar cutter.

FIG. 4 is a bottom view of a double cigar cutter.

FIG. 5 is a left side elevation view of a double cigar cutter.

FIG. 6 is a right side elevation view of a double cigar cutter.

FIG. 7 is a front view of a double cigar cutter; and,

FIG. 8 is a rear view of a double cigar cutter.

The broken lines shown are included for the purpose of illustrating portions of the double cigar cutter that form no part of the claim.

1 Claim, 4 Drawing Sheets
